UNITED STATES PATENT OFFICE

2,476,114

ELECTRIC BURGLAR ALARM

Kathyrine Regan, New Orleans, La.

Application March 1, 1948, Serial No. 12,430

1 Claim. (Cl. 200—163)

1

This invention relates to improvements in burglar alarms of the class in which a sash, door or other closures become the medium of actuation for the alarm.

An object of the invention is to provide an alarm of the type that is inexpensive to manufacture, easily installed and designed to operate on a low voltage electric current.

The burglar alarm embodying the invention may be used in homes or offices, on automobiles or any other place where access is obtained through a closure.

The alarm may be used with a house door bell wiring system or any place that a bell or voltage reducer is installed. On automobiles, it can be connected directly to the battery and horn.

The alarm will sound continuously until the switch controlling the system has been turned off, or until each unit has been nullified.

On an unoccupied house, it would notify the police and neighbors that someone is attempting to gain access thereto.

With the above and other objects and advantages in view, the invention consists of the novel details of construction, arrangement and combination of parts more fully hereinafter described, claimed and illustrated in the accompanying drawing in which:

Figure 1 is a partial elevational view of a closure having a signal embodying the invention mounted for cooperation therewith, and interpolated in the bell wiring of the habitation;

Figure 2 is a vertical, sectional view on the line 2—2 of Figure 3, with the alarm in inoperative position;

Figure 3 is a vertical, sectional view on the line 3—3 of Figure 2;

Figure 4 is a cross sectional view on the line 4—4 of Figure 2;

Figure 5 is a cross sectional view on the line 5—5 of Figure 2;

Figure 6 is a view similar to Figure 2, with the alarm in operating position;

Figure 7 is a view similar to Figure 3, with the alarm in operating position.

Referring more in detail to the drawing, the reference numeral 10 designates the alarm embodying the invention.

The alarm comprises a box-like body 11, which is made of a colored plastic material. The color of the plastic is adapted to harmonize with the support to which it is attached.

In Figure 1, the alarm 10 is shown mounted on a window frame 12, having a window sash 13. The mounting of the alarm 10 is accomplished by

2

fasteners 14 passing through the removable face plate 15 to enter the frame 12.

The inner face of the rear wall 16 of the body 11 is provided with two vertically disposed parallel spaced grooves 17 and 17' respectively, in which are positioned the sprung metal conductors 18 and 18' respectively. Secured to the inner face of the rear wall 16 over the conductors 18 and 18' respectively is the plastic plate 19 that retains the conductors in their respective grooves.

The lower end of each conductor has a foot portion 20 which engages the inner face of the bottom wall 21 of the body 11, and a post 22 is connected to each foot portion 20 of the conductors.

Wires 23 connected to the posts are interpolated in the bell wiring system 24 of the house in which the frame 12 is installed.

The upper end of each conductor is formed in a contact helical 25, which, curving downward, will, in non-contacting position, rest on or engage the outer face of the plate 19.

Slidably engaging the plate 19, is the contact blade 26. The outer ends of the blade are rolled over at 27 to engage the lower ends of the parallel portions 28 of the U-shaped actuating member 29. The blade is soldered at its engagement with the portion 28 to prevent the blade from becoming loosened from the ends. The parallel portions 28 of the member 29 extend upwardly and outwardly of the body 11, through spaced openings 29' formed in the top wall 21' of the body 11.

The cross piece 30 of the member 29, outwardly of the body 11, is provided with an eye formation 31, to which a cord 32 is connected, and the cord 32 has a snap hook 33 connected to its free end.

The cover 15 has a centrally located, vertically disposed guide plate 34 adhesively affixed thereto, and the plate engages the blade 26 to retain it in fully sliding engagement with the plate 19. The plate 34 is interposed between the helicals 25 of the conductors 18.

Adhesively connected to the plate 19, in horizontal relation thereto, and in contact with the lower edge of the plate 34, is the stop or rest plate 35, on which the blade 26 rests when the alarm is in non-sounding position.

In use, the alarm 10 is fixed to a support, as previously described. The cord 32 is trained through guide screw eyes 36 affixed to the support, and the snap hook 33 is engaged with a screw eye 37 in the sash 13.

Should anyone attempt to raise the sash 13, the cable 32 will be pulled, exerting an upward move-

ment on the member 30 to raise the blade 26 into contact with the helicals 25 to energize and sound the bell 38 in the system 24.

It will be noted that the upper edge of the blade 26 is sharpened as at 39 to provide a knife edge whereby the blade will easily slip under the helicals 25. Once engaged with the helicals, the helicals will hold the blade in this position until the member 29 is pushed downwardly by the owner of the house in which the alarm is installed.

In installation, the body 11 must be fastened so that the blade 26 will move in a vertical plane. Thus the plate 34 will always maintain the blade in true operating relation to the helicals 25.

While the invention has been shown and described in use with a window sash, it is to be understood that it can be used with any type of closure that must be opened, to gain access to the enclosure on which the closure is mounted.

It is believed that from the foregoing description, the manner of construction and operation of the alarm will be apparent to those skilled in the art, and it is to be understood that changes in the minor details of construction, arrangement and combination of parts may be resorted to, provided they fall within the spirit of the invention and the scope of the appended claim.

Having thus described the invention, what is 30

claimed as new and desired to be secured by Letters Patent is:

A device of the character described, comprising a box-like body, vertical grooves in the body, conductors in the grooves, a helical formation at the upper end of each conductor, posts connected to the lower ends of the conductors for connecting the conductors to an electrical circuit, an insulating plate over the conductors adapted to hold the conductors in their respective grooves, a contact blade slidably engaging the plate, a U-shaped member passing through the upper end of the body and connected to the blade to slide the blade into engagement with the helical formation of the conductors, a knife edge on the blade to permit easy insertion of the blade into the helical formation, a rest plate for the blade and a guide plate for the blade, both carried by the body.
